UNITED STATES PATENT OFFICE.

JOSEPH E. BOHNER, OF ANSONIA, CONNECTICUT.

DESIGN FOR A LAMP-BASE.

SPECIFICATION forming part of Design No. 24,435, dated June 25, 1895.

Application filed May 11, 1895. Serial No. 549,014. Term of patent 3 $\frac{1}{2}$ years.

To all whom it may concern:

Be it known that I, JOSEPH E. BOHNER, a citizen of the United States, residing at Ansonia, in the county of New Haven and State of Connecticut, have invented and produced a new and useful Design for Lamp-Bases, of which the following is a full and complete specification, reference being had to the accompanying drawing, which illustrates the design.

The drawing illustrates a lamp-base embodying my design, the same being shown in perspective position.

The general outline of the base is of the truncated form illustrated.

The design consists of the socket A flaring outwardly as shown and grooved at B. Below

this socket appears the perforated band of flower and scroll work C. D is a plain belt surrounding the base. The lower edge of the base consists of the open flower, shell and scroll work E, F and G. H represents the feet of the base which are of the disk and scroll form shown. These are the essential features of the design.

What is claimed as new is—

The design for lamp bases and similar articles, substantially as herein shown and described.

JOSEPH E. BOHNER.
